(57) **CLAIM**

The ornamental design for an aerosol generating device, as
shown and described.

DESCRIPTION

FIG. 1 is a front, top, and left side perspective view of an
aerosol generating device showing the new design in an
environment of use;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front, bottom, and right side perspective view of
an aerosol generating device showing the new design
removed from environment for clarity and disclosure;

FIG. 9 is a front elevational view thereof;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof; and,

FIG. 15 is a rear, top, and right side perspective view thereof.
The broken lines in the drawings show environmental sub-
ject matter only and form no part of the claimed design.
